ERASEPATHOGENS

Surface Cleaning System

OPERATING ROOM Clean by Sequence High-Touch Surfaces Map

Using a disinfectant and your Clean by Sequence Microfiber Cloths, clean and disconnect each surface in the order shown.

BIOHAZARDES

- 1. GR/AB, OR Mattress
- 2. GR/AB, OR Monitor
- 3. Arms of Table, Bed, Control and Body Straps
- 4A/AB, OR Mattress
- 5A/AB, OR Table

ANESTHESIA

- 1. Monitor/Ventilator and Bedside Monitor/Mac-10 Wheel
- 2. Ventilator and Suction Station
- 3. Soda Lime Bag
- 4. Ties and Straps
in Anesthesia Cart
- 5A/AB, Anesthesia Cart
- 6. IV Pole

TERMINAL SURFACES/STAN-BETWEEN IF USED OR SOILED

- Open and Closed door
- Light fixtures
- Litter handles/holder
- Trolley
- Open and Closed door
- Light fixtures
- Wristbands/ID holder
- Step stool
- Clotter machine
- Neck buckle
- Roller Board
- Back table
- Wristbands/ID holder
- Positioning devices (gloves, gel/foam supports, etc.)
